UNITED STATES PATENT OFFICE.

PETER THOMSEN, OF CASSEL-WILHELMSHÖHE, GERMANY, ASSIGNOR TO SCHMIDT'SCHE HEISSDAMPE GESELLSCHAFT M. B. H., OF CASSEL-WILHELMSHÖHE, GERMANY, A CORPORATION OF GERMANY.

APPARATUS FOR COOLING SUPERHEATER-PIPES.

1,072,194.

Specification of Letters Patent.

Patented Sept. 2, 1913.

Application filed May 14, 1913. Serial No. 767,809.

To all whom it may concern:

Be it known that I, PETER THOMSEN, a subject of the King of Prussia, Emperor of Germany, residing at Cassel-Wilhelmshöhe, 5 Germany, have invented a new and useful Improvement in Apparatus for Cooling Superheater-Pipes in Steam-Superheaters for Locomotives and other Engines, of which the following is a specification.

- 10 My invention relates to steam superheaters for locomotives and other engines, and particularly to such superheaters when used in engines having a short chimney, so that a blower is necessary for increasing the draft. 15 In engines of the above described type, the blower is ordinarily operated by the exhaust from the engine cylinders, so that when the engine is running idle (coasting), or is stationary, the blower must be started in order 20 to supply sufficient draft to maintain the steam supply. When the blower is thus operating alone with the steam supply cut off, there is, of course, no steam flowing through the superheater pipes. Under such circumstances, these pipes are very apt to overheat and to burn out.

It is the object of my present invention to provide a means whereby steam or air or a mixture of the two may be carried through 25 the superheater pipes when the steam supply to the engine cylinders is cut off and the blower is running in order that the pipes may be made sufficiently cool and prevented from burning out.

30 More particularly, it is the object of my invention to provide means whereby a certain part of the steam which is admitted to the blower pipe is diverted to the saturated steam header and from thence passed through 35 the superheater pipes to be released to the atmosphere through suitable drain cocks, valves or other openings.

Another object of my invention is to so 40 arrange the steam connections to the saturated header through which steam from the blower pipe is carried that when the engine is running idle (coasting), air will be automatically drawn into and through the superheater pipes.

45 My invention will be better understood by referring to the accompanying drawings in which the several embodiments of the same are illustrated.

A preferred embodiment of my invention is shown in Figure 1, which is a central vertical section through the end of a boiler equipped with my invention; Fig. 2 is a similar view showing a modified form of my invention; and Fig. 3 is a view similar to Fig. 1 showing still another modification of the 6 invention.

Referring to Fig. 1, a boiler *a*, a smoke box *b* and tube sheet *c* are arranged in the usual manner, the boiler being provided with a certain number of enlarged fire tubes *d* in 65 which are disposed superheater tubes *e* of known type. These superheater pipes are connected to a steam header *f* comprising saturated and superheated steam chambers *g*, *h* respectively, the saturated steam entering the saturated steam chamber *g* through an inlet opening *i* after having passed through a suitable pipe and throttle (not shown). After passing through the superheater pipes, the superheated steam is conducted through pipe *j* to the engine cylinders (not shown). A blower pipe *k* terminates above the cylinder exhaust pipe *l* in a ring which surrounds the aperture of said blower pipe, this ring being provided with 80 openings *m* on its upper side constituting outlets. The blower supply pipe *k* leaves the boiler at any convenient point and is provided with a blower cock *o* by means of which the blower is controlled. At some 85 suitable point the cock *o* and the outlets *m* a branch connection *m'* controlled by a valve *r* is disposed. From some other point in the blower supply pipe *k* is a branch connection *n* controlled by a check valve *q* and opening 90 into a pipe *p*; this pipe *p* opens into the saturated steam chamber *g*.

The operation of the arrangement is as follows: The steam supply to the engine cylinder being cut off by closing the main 95 throttle, and the blower started by opening cock *o*, part of the steam which passes into pipe *k* through cock *o* will branch off through the valve *q* and pipe *p* into the saturated steam chamber *g* from whence it will 100 pass through the superheater pipes to the chamber *h* and then be discharged into the atmosphere through suitably disposed drain cocks, valves or other openings on the engine or on the steam supply pipes leading thereto. During the normal working of the engine

when the draft is being produced solely by the exhaust through exhaust pipe *l*, the flow of steam through the superheater pipes is sufficient to prevent their overheating; in such cases, the blower is not used and the cock *o* is kept closed. The check valve *q* prevents steam from the header passing back through pipe *p* and out through blower pipe *k* to the atmosphere. On first starting up, when there is, of course, no steam pressure in the boiler and hence no steam in the superheater pipes, the pipe *r* may be connected to any suitable supply of compressed air and the valve *n* opened. This air will then flow through the superheater pipes and keep them cool.

In the modification shown in Fig. 2, the pipe *p* enters directly an air valve *s* which valve is itself fixed to the top of and opens into the saturated steam chamber *g* of the header. This air valve is of the type frequently provided on locomotives for preventing the formation of a vacuum in the cylinders and in the slide valve chests when the engine is running with throttle closed. As steam passes through pipe *p* into the valve *s*, the arrangement acts like an injector and air is drawn through holes *t* so as to mix with the steam and pass into the steam chamber *g* and thence through the superheater tubes. The valve member *u*, when the throttle is open and normal steam pressure exists in chamber *g* closes and prevents any steam loss through the holes *t* to the atmosphere.

While the arrangement shown in Fig. 2 is somewhat more complicated than that shown in Fig. 1, it is, on the other hand, more efficient, since the cooling effect of air drawn from the outer atmosphere is greater than that of steam taken from the boiler. A further advantage of the arrangement shown in Fig. 2 is that when the engine is coasting with regulator closed, it is not necessary to have the blower in operation, as the suction of the engine cylinders causes a sufficient quantity of cold air to be drawn through the air valve into the superheater.

The use of a single valve upon the header, instead of a valve on each cylinder prevents the formation of a vacuum on the cylinder just as effectively and has the additional advantage that smoke and dirt from the exhaust pipe cannot be drawn into the cylinders and into the valve chest.

Fig. 3 shows still a third form of my invention. This is very similar to the construction shown in Fig. 2, but has the advantage that only one check valve is required for preventing boiler steam from escaping when the throttle is open. In this form, when the blower is operated with the throttle open, a portion of the medium for operating the blower escapes from the blower pipe through

the branch pipe *p* and the apertures *t*; the loss due to this is, however, quite small. 65

In all of the several forms above described, it is not essential that the branch from the blower pipe shall open directly into the saturated steam chamber, as the same result will be attained if said branch opens at any 70 other convenient point between the throttle and the saturated ends of the superheater pipes.

The cross section of the drain cocks or air valves through which the steam passes 75 into the atmosphere after having gone through the superheater pipes must obviously be sufficiently great to prevent such an increase of pressure in the valve chest or cylinder as might possibly cause the engine to start up. This cross section should obviously be greater than the cross section of the blower pipe.

Having described my invention, I claim:

1. In a boiler provided with fire tubes, in 85 combination, superheater tubes in some of said fire tubes adapted to have their steam supply cut off, a blower pipe connected with the boiler by a cock and provided with a nozzle, a branch pipe opening from the 90 blower pipe between said cock and nozzle and joined to the saturated end of the superheater elements, and a check valve controlling said branch pipe.

2. In a boiler provided with fire tubes, in 95 combination, superheater tubes in some of said fire tubes adapted to have their steam supply cut off, a blower pipe connected with the boiler by a cock and provided with a nozzle, a branch pipe opening from the 100 blower pipe between said cock and nozzle and joined to the saturated end of the superheater elements, a check valve controlling said branch pipe, and a second branch connection from the blower pipe adapted to be 105 joined to a pressure source other than the boiler.

3. In a boiler provided with fire tubes, in combination, superheater tubes in some of said fire tubes adapted to have their steam 110 supply cut off, a blower pipe connected with the boiler by a cock and provided with a nozzle, a branch pipe opening from the blower pipe between said cock and nozzle and joined to the saturated end of the superheater elements, air inlet passages in said 115 branch pipe, and a check valve between said passages and the superheater elements for controlling the branch pipe.

In testimony whereof, I have hereunto set 120 my hand in the presence of two subscribing witnesses.

PETER THOMSEN. [L. S.]
